Des. 179,762

PAGE 3

Figure 1 is a bottom perspective view of an airplane embodying our new design.

Figure 2 is a bottom perspective view similar to Figure 1 but showing the rotary stores carrier door in the open position.

Figure 3 is a top plan view of the airplane.

Figure 4 is a front elevational view of the airplane.

Figure 5 is a side elevational view of the airplane.

We claim:

The ornamental design for an airplane, as shown.
